FIG. 2 is a front perspective view of the front shroud for a floor maintenance vehicle of my design;
FIG. 3 is a front elevation view thereof;
FIG. 4 is a top plan view thereof;
FIG. 5 is a right-side elevation view thereof;
FIG. 6 is a left-side elevation view thereof;
FIG. 7 is a rear elevation view thereof; and,
FIG. 8 is a bottom plan view thereof.
Where included, broken lines showing environment or structure are for illustrative purposes only and form no part of the claimed design.
